EYEGLASS FRAME

Yumatsu Murai, Fukui, Japan, assignor to
Welling International Corp.

Filed July 9, 1973, Ser. No. 377,704

Term of patent 3½ years

Int. Cl. D16—06

U.S. Cl. D57—1 F

Fig. 1.

Fig. 2.

Fig. 3.

FIG. 4.FIG. 5.FIG. 5.FIG. 7.FIG. 1 is a side elevational view of the eyeglass frame showing my new design, the opposite side elevational view being identical;

FIG. 2 is a top plan view of the eyeglass frame shown in FIG. 1;

FIG. 3 is a front elevational view of the eyeglass frame shown in FIG. 1;

FIG. 4 is a rear elevational view of my eyeglass frame showing the temple members folded;

FIG. 5 is a bottom plan view of the eyeglass frame in FIG. 4;

FIG. 6 is a sectional view taken along line 6—6 of FIG. 2; and

FIG. 7 is an enlarged cross sectional view taken along the line 7—7 of FIG. 6.

I claim:

The ornamental design for an eyeglass frame, substantially as shown and described.
